Specification for Design.

Patented Aug. 30, 1921.

Application filed February 4, 1921. Serial No. 442,549. Term of patent 14 years.

To all whom it may concern:

Be it known that I, HARRY D. LILLIBRIDGE, a citizen of the United States, residing at Zanesville, State of Ohio, have invented a new, original, and ornamental Design for Wall-Receptacles, of which the following is a specification, reference being had to the accompanying drawings, forming a part hereof.

In the drawings,

Figure 1 is a perspective view of a wall receptacle showing my new design.

Figs. 2 and 3 are views in vertical cross section and in horizontal cross section on the lines 2—2 and 3—3 respectively of Fig. 1.

I claim:

The ornamental design for a wall receptacle, as shown.

HARRY D. LILLIBRIDGE.
